G. L. BROWNELL

SPOOL SUPPORT FOR TWISTING MACHINES AND THE LIKE

Filed March 29, 1927

INVENTOR:
George L. Brownell
By Owen W. Kennedy
Attorney

UNITED STATES PATENT OFFICE.

GEORGE L. BROWNELL, OF WORCESTER, MASSACHUSETTS.

SPOOL SUPPORT FOR TWISTING MACHINES AND THE LIKE.

Application filed March 29, 1927. Serial No. 179,367.

My invention relates to an improved support for the spools employed on the twisting machines and the like, wherein the spools are rotated at a relatively high speed while the twisted, or other material, is wound on the spools by fliers rotating at a slightly higher speed than the spools themselves. In such machines as heretofore constructed each spool has been freely rotatable on a vertical spindle carrying the flier with one head of the spool resting on a rail to which an up and down motion is imparted in order to traverse the material being wound on the spool.

With this construction there is naturally considerable friction between the head of each spool and the supporting rail and between the body of the spool and its spindle, and when the machine is operated at a high speed, a considerable amount of heat is generated by this friction between relatively movable surfaces. Inasmuch as the wooden spools heretofore employed tend to char and warp, due to the heat generated, it has been found that a very definite limitation is imposed on the speed at which machines of this type can be safely operated when employing spools constructed of wood or other nonmetallic material having poor heat dissipating qualities.

The object of the present invention is to provide an improved support for the spools of twisting machines and the like, whereby any heat generated by the rotation of the spools is quickly dissipated, so that there is no appreciable heating of the spool and its associated parts, even when the machine is run at speeds not heretofore considered practicable. My improved spool support in addition to its heat dissipating properties is also so constructed as to insure that the associated spool will always be correctly aligned on its spindle, thereby insuring the formation of an even winding on the spool. The above and other advantageous features of my invention will hereinafter more fully appear, reference being had to the accompanying drawings, in which—

Fig. 1. is a view partly in vertical section and partly in elevation illustrating my invention with the associated parts of a twisting machine.

Fig. 2 is a view taken from in front of the spool rail showing the parts of Fig. 1 on a reduced scale.

Fig. 3 is a horizontal sectional view along the line 3—3 of Fig. 1.

Fig. 4 is a horizontal sectional view along the line 4—4 of Fig. 1.

Like reference characters refer to like parts in the different figures.

Referring to Figs. 1 and 2, my invention is shown for purposes of illustration in connection with parts of a twisting machine, although it is to be understood that my invention may also be employed in connection with the support of rotatable spools employed on similar types of machines. In this particular embodiment of my invention each spool consists of a cylindrical barrel 1, preferably of wood, provided at its ends with heads 2 composed of wood, compressed fibre, or any similar light weight material. A vertical spindle 3 extends through the bore 4 of the barrel 1, the spindle 3 being supported at its top and bottom in suitable bearings 5, only portions of which are shown.

The spindle 3 carries a gear 6, whereby a rotative driving force may be imparted thereto from a source of power, not shown, and a flier 7 is also carried by the spindle and rotatable therewith. The flier 7 provides downwardly extending hollow legs 8, 8, through either one of which the material to be wound on the barrel 1 of the spool passes to the spool, as indicated at 9. The material 9 is led downwardly through the upper portion of the spindle 3 and emerges from an eye 10 to pass around a positively driven take-up drum 11 before passing into the leg 8 of the flier 7.

As previously pointed out the spool is free on its spindle 3 and is adapted to be positioned thereon by means of a spool rail 12 which is adapted to have an up and down motion imparted thereto by means not shown, since it forms no part of the present invention. As the flier 7 is rotatably driven at a high rate of speed it slowly winds the twisted, or other material 9, on the barrel 1 while at the same time the spool turns at a rate only slightly less than that of the flier. The difference in speed between the flier 7 and the spool results from the frictional retardation of the spool, and it is the object of my invention to dissipate the heat resulting from this friction by an improved construction which will now be described.

The bore 4 of the spool barrel 1 is of such

diameter as to closely receive a sleeve 13, preferably composed of light metal that readily conducts heat, such as aluminum, and this sleeve 13 provides suitable bearing surfaces 14 at its ends for engagement with the spindle 3. The sleeve 3 terminates at its lower end in a circular flange or plate 15, preferably formed integral therewith, the plate 15 being in contact with the lower head 2 of the spool. An annular disk 16, also composed of light heat conductive material, such as aluminum, is secured to the plate 15 in spaced relation therefrom by means of screws 17 arranged in staggered relation around the outer periphery of the plate 15.

As best shown in Fig. 4, a plurality of spacers 18 surround the screws 17 to firmly space the disk 16 from the plate 17, the spacers 18 also being composed of good heat conducting material, such as copper. Two of the screws 17^a are provided with enlarged heads 19 which extend upwardly above the plate 15 and are received in suitable holes 20 provided in the spool head 2. Thus the spool and its support are locked together and rotate as a unit when the machine is operated.

With the above described construction it is obvious that as the spool rotates at a speed slightly less than that of the flier 7, the heat generated by friction between the lower annular disk 16 and the spool rail 12 will be quickly dissipated, due to the open construction of the spool support, and the fact that it is constructed of material that quickly dissipates heat. Furthermore, the cooling effect is increased by the fact that the spacers 18 tend to act as vanes to set up a circulation of air as the spool rotates. With this action it is apparent that practically no heat can be conducted to the spool itself, so that the flier 7 can be operated at speeds not heretofore obtainable without danger of charring or warping the spools, due to heat generated by contact with the spool rail 12.

While, as previously pointed out, the

spool itself tends to operate as a unit with my improved support, it is possible to separate the spool proper from the metal support 50 after doffing, so that it is not necessary to provide a cooling support for each spool. It is entirely within the scope of my invention, however, to construct the spool support of such light and relatively inexpensive material as to warrant the permanent connection of each spool to its support, particularly under conditions where the increase in the life of the spools warrants the extra expense of the heat dissipating support. I desire, therefore, that only such limitations be imposed on my invention as come within the scope of the appended claims.

I claim:

1. As a new article of manufacture, a wooden spool comprising a cylindrical barrel and heads, one head having attached thereto heat dissipating means including metal disks with staggered spacing members therebetween.

2. In a spool support, a vertical spindle, a metal sleeve loosely mounted on said spindle and providing a flange at its lower end, a wooden spool having its barrel closely fitting on said sleeve with its lower head 75 secured to said flange and a metal plate secured to said flange by spacers for supporting said sleeve and spool, whereby heat generated by the rotation of the sleeve and spool is dissipated in the spaced flange and plate. 80

3. As a new article of manufacture, a wooden spool comprising a cylindrical barrel and heads, one head having attached thereto heat dissipating means including spaced metal disks, hollow cylindrical metal 85 spacers between said disks, and screws passing through said spacers to hold said disks together, the spacers and the disks serving to dissipate the heat and the cylindrical spaceis also covering the threads of the 90 screws in order that the device shall not accumulate lint.

GEORGE L. BROWNELL.
